REMOVABLE POURING SPOUT

Zeth F. Ahlquist, Chicago, Ill., assignor to Zeth F. Ahlquist and Allan R. Nilson, general partners, and Olaf G. Nilson, Edna Nilson, J. Edward Martin, Hildur S. Martin, Carl B. Olson, and Frances H. Ahlquist, limited partners, doing business under the firm name of International Machine and Tool Works, Chicago, Ill.

Application March 30, 1953, Serial No. 345,461

3. Claims. (Cl. 222—527).

The present invention pertains to removable pouring spouts for use with liquid containers such as emergency gasoline cans, oil cans, and the like, and has particular relation to such spouts having improved crimp fabricated construction obviating the necessity for soldering the parts together.

In the mass production and use of removable spouts for gasoline cans and the like, the required heat and flux for soldering together the various tin-plated parts mars the appearance of the article and subjects it to easy rusting. As a result such spouts usually have to be painted, which is an undesirable attempt to remove the difficulty since the painting operation is relatively expensive and the paint itself easily chipped in use, or perhaps removed by solvents poured through the spout.

It is therefore an object of the present invention to provide a simple, effective, and economically made removable pouring spout of the type described which may be fabricated of tin-plated parts without the necessity for soldering and with the removal of the difficulties mentioned above.

Further objects and advantages of the invention will become apparent as the following description proceeds, taken in conjunction with the accompanying drawing, in which:

Figure 1 is a fragmentary perspective view of a liquid container or can equipped with a pouring spout embodying the present invention;

Fig. 2 is a vertical section of a cap employed in the present spout and shown prior to assembly;

Fig. 3 is a vertical section of the cap and a cooperating thimble or sleeve illustrating a step in the assembly of the present spout;

Fig. 4 is an exploded elevation, partially in section, illustrating another step in the assembly of the present spout;

Fig. 5 is a fragmentary vertical elevation of the present spout;

Fig. 6 is a fragmentary vertical section of the completely assembled spout;

Fig. 7 is a plan view, partially in section along line 7—7 in Fig. 5, of the spout of the present invention; and

Fig. 8 is a vertical section of a partially assembled pouring spout embodying a modified form of the present invention.

While particular embodiments of the present invention are shown and described in some detail, it is not intended that the invention be thereby limited. On the contrary, the intention is to cover all alterations, modifications, and equivalents falling within the spirit and scope of the invention as defined by the appended claims.

Referring now to the drawing, the removable pouring spout of the present invention is shown in Fig. 1 as attached to a liquid container 10 of conventional form having an orifice surrounded by a threaded neck (not visible). The spout is formed of tin-plated sheet metal parts of unique configuration which are crimped or clamped together without any necessity for soldering or

2

painting. As shown in Figs. 1 and 6, it comprises an apertured cap 11 adapted to be threaded on the neck of the container 10. The margins of a central opening 12 in the top of the cap are crimped in the form of a collar 13 extending upwardly and outwardly over an inturned flange 14 of an abutting cup-like thimble or sleeve 15. A metal ferrule 16, which is crimped to one end of a pouring tube 17, is received within the upstanding thimble and secured by peripheral crimping or clamping. The thimble 15 is thus securely attached to the cap 11 around its central opening 12 and the ferrule 16 and tube 17 are securely clamped within the thimble. The resultant spout is simple in nature and easily assembled, at the same time being leak-proof and formed without the use of solder on a soldering operation.

A further description of the individual components and final construction of the pouring spout may best proceed by reference to the steps in its assembly, as illustrated by Figs. 2 through 6. In Fig. 2 the base or cap 20 for the spout is shown in its initial configuration as a generally cylindrical member having a skirt 18 formed to be screwed on the threaded neck of the can 10. While various arrangements may be used for the removable attachment of the cap to the can, a threaded connection is convenient and is shown. The cap 11 has a central aperture or opening 12 defined in its top portion 19 with an initially upstanding collar or flange 13 surrounding the opening.

As shown in Fig. 3, the first step in assembly is the positioning of the generally cylindrical and cup-like thimble or sleeve 15, having an inturned circular flange 14 on its lower end, over the upstanding collar 13 with the flange 14 abutting top portion 19. The collar 13 is crimped outwardly over the flange 14 to lock the cap 11 and thimble 15 together (Fig. 4). A strainer or screen 20 may optionally be pressed inside the thimble to form an integral part of the spout, held in place by ferrule 16.

As illustrated more completely in Figs. 1 and 4, a length of tubing 17, in this instance a spirally constructed flexible metal hose, is equipped with ferrules 16 extending over either end, the ferrules being crimped onto the hose by inturned collars 21 at their extremities. The tubing or hose 17 is secured to the cap 11 and thimble 15 by the insertion of one ferrule 16 into the thimble. The two parts are then positively crimped together along peripheral squeeze lines 22 resulting in vertical pinched ears 23 (Figs. 5 and 6). A unitary pouring spout is thus formed without any necessity for soldering, but through simple crimping operations of cooperating elements results in a strong, simple, and leak-proof construction. The spout may be removably attached to the neck of a container formed to cooperate with the skirt of the cap and the flexible hose may be swung to any angle during pouring operations.

In Fig. 8 there is shown a partially assembled pouring spout embodying features of a modified form of the invention intended to facilitate the storage of the spout within, and the closure of, the container when the spout is not in use. In this embodiment, two caps 11 and 11a similar to that described above are positioned and secured in back-to-back relation, the lower cap 11 having a collar 13 around its central opening 12 crimped to extend through the opening 12 of the upper cap 11a. The upper cap 11a is formed without such a collar. The two caps and a thimble 15 having an inturned flange 14 are all secured together as shown by the crimped collar 13 of the lower cap bent outwardly to engage the inner side of the flange 14, with the outer side of the flange abutting against the top portion 19 of the upper cap 11a and securing it against the top portion of the lower cap 11. The pouring tube or hose, with a ferrule on

its end (not shown in Fig. 8), may then be crimped within the thimble 15 as described above.

The modified spout shown by Fig. 8 may be employed as a removable spout by attaching the lower cap 11 to the neck or orifice of a container in the same manner as the first embodiment described. However, when the spout is not in use and the container is to be closed, the caps may be inverted and the upper cap 11a placed over the neck of the container with the tubing or hose extending into the interior of the container in stored position. A suitable closure plug (not shown) may then be screwed into the lower cap 11a to seal the container.

From the foregoing description, it will be apparent that the pouring spout of the present invention provides a simple, strong, and leak-proof construction easily fabricated by crimping, spinning, or stamping operations of tin-plated sheet metal parts without any necessity for a soldering operation. For this reason, the spout, when complete, is not marred or disfigured and presents a pleasing appearance without the necessity of painting.

I claim as my invention:

1. A removable spout for a container comprising at least one cap adapted to be removably attached to an orifice of the container and having a top portion with an aperture therein and a peripheral collar around the aperture, a cup-like thimble having a central opening in its bottom registering with said aperture and bordered by an inturned flange, said collar being crimped over said flange on its inner side to secure the thimble and cap together, a length of tubing, and a ferrule rigid with one end of said tubing, said ferrule and thimble being peripherally crimped together.

2. A removable spout comprising at least one threaded cap adapted to be screwed on a threaded neck of a container, said cap having an aperture in its top and a collar surrounding said aperture, a cup-like sleeve having an inturned flange on one end positioned to rest on said top with said collar extending into said sleeve and crimped around and over said flange to secure said sleeve to said cap, a flexible metal hose, and a ferrule crimped to one end of said hose, said ferrule being located within said sleeve and peripherally crimped in said sleeve.

5 3. A removable spout for a container having a threaded neck, said spout comprising two cylindrical threaded caps having apertured top portions placed back to back, one of said top portions having a cylindrical collar around its aperture extending through the aperture of the other top portion, a thimble having an opening in its bottom defined by a flange extending inwardly from its sides, said thimble abutting said other top portion with its flange surrounding said collar, said collar being crimped outwardly to overlie said flange and secure said two caps and said thimble together, a ferrule circumferentially crimped within said thimble, and a tube having one end crimped in said ferrule.
